REFRIGERATION

William R. Hainsworth, Larchmont, N. Y., assignor to Servel, Inc., New York, N. Y., a corporation of Delaware

Application October 6, 1939, Serial No. 298,163

7 Claims. (Cl. 62—119.5)

My invention relates to refrigeration and more particularly to an absorption refrigerating apparatus of the continuous cycle and constant pressure type.

Among the objects of my invention is to provide a refrigerator having two evaporators arranged to be maintained at different temperatures. The evaporator which operates at the low temperature is utilized for freezing ice, while the higher temperature evaporator serves to maintain the desired temperature in the food compartment of the refrigerator cabinet.

A further object of my invention is to locate the lower temperature evaporator within the higher temperature evaporator in order to reduce the flow of heat from the food space of the refrigerator to the lower temperature evaporator. This results in a lower temperature being maintained in the ice freezing compartment.

Further objects and advantages of my invention will be apparent from the following description considered in connection with the accompanying drawings which form a part of this specification and of which:

Fig. 1 is more or less a diagrammatic view, partially in cross section, showing a preferred embodiment of my invention;

Fig. 2 is a cross-sectional view showing an evaporator constructed in accordance with my invention within a refrigerator cabinet.

Fig. 3 is a cross-sectional view on an enlarged scale of the evaporator shown in Fig. 2 and is taken on the lines 3—3 of Figs. 4 and 5;

Fig. 4 is a cross-sectional view taken on the lines 4—4 of Figs. 3 and 5; and

Fig. 5 is a cross-sectional view taken on the line 5—5 of Fig. 4.

Referring more particularly to Fig. 1 reference character 10 designates a generator or boiler which includes a centrally located flue 11 and an outer shell 12. A transverse partition 13 divides the space within shell 12 into chambers 14 and 15. Chamber 14 constitutes a pumping chamber and is provided with a dome 16. A vapor lift conduit 17 extends through dome 16 from within chamber 14 and communicates with the upper end of a stand pipe 18. The lower end of stand pipe 18 is connected to the upper part of chamber 15. Any suitable source of heat, such as the gas burner 19, is provided for heating the flue 11 and the contents of chambers 14 and 15.

A conduit 20 is connected to the upper end of stand pipe 18 and is provided along the portion of its length with heat transfer fins 21. This portion thus constitutes a rectifier. The upper

end of conduit 20 communicates with a condenser indicated generally by reference character 22. This condenser is made up of an upper part 23 and a lower part 24. The lower end of the upper part 23 communicates with a vessel 25. The upper end of lower part 24 also communicates with vessel 25 and with a vessel 26.

Reference character 27 designates generally an evaporator located within a refrigerator cabinet 28. The evaporator is made up of a low temperature part 29 and a high temperature part 30. A conduit 31 leads from the bottom of vessel 25 to the upper end of the low temperature part 29, while a conduit 32 leads from the bottom of vessel 26 to the upper end of high temperature part 30. A conduit 33 connects the lower end of low temperature part 29 with the upper end of high temperature part 30. A conduit 34 forming a liquid trap, connects the lower end of conduit 33 with a conduit 35 which leads from the lower end of high temperature part 30.

Reference character 36 designates generally a gas heat exchanger having an inner pipe 37, and an outer jacket 38. Conduit 35 is connected to the upper end of inner pipe 37, while the lower end of this pipe is connected to the lower part of an absorber 39. A conduit 40 connects the upper end of the absorber with the lower end of jacket 38, while a conduit 41 connects the upper end of this jacket with the upper end of low temperature part 29 of the evaporator.

A conduit 42 leads from the lower part of absorber 39 to the outer jacket 43 of a liquid heat exchanger 44, while a conduit 45 connects the other end of this jacket with pumping chamber 14 in the generator. A conduit 46 leads from chamber 15 of the generator and passes within jacket 43 of the heat exchanger. The other end of conduit 46 communicates with the upper part of the absorber 39. It will be noted that the upper end of conduit 46 is below the upper end of vapor lift pipe 17, whereby liquid discharged from the upper end of pipe 17 will flow by gravity to the upper end of absorber 39.

A coil 50 is in heat exchange relation with absorber 39 and is connected by means of conduits 51 and 53 with a condenser 52. The closed circuit comprised of coil 50, conduits 51 and 53, and condenser 52 is partially filled with a fluid which, under the pressure prevailing in this circuit, boils in coil 50 at the temperature at which it is desired to maintain the absorber and condenser in condenser 52 at atmospheric temperature.

A pressure vessel 54 is connected to vessel

26 by means of a conduit 55, and to the upper end of pipe 31 by means of a conduit 56.

The above identified application operates as follows:

The generator 10 and associated conduits are charged with a solution consisting of a refrigerant absorbed in an absorption medium. For instance, the absorption medium may be water and the refrigerant ammonia. A gas inert with respect to both the refrigerant and the absorption medium, such as hydrogen, is also introduced into the system.

The application of heat to the solution of ammonia in water, contained within generator 10, causes ammonia vapor to be driven off in both chambers 14 and 15. The gas thus produced in pumping chamber 14 enters the lower end of vapor lift conduit 17 along with liquid, and the gas serves to lift such liquid through the conduit 17 to the upper end of stand pipe 18. The liquid flows downwardly through the stand pipe while ammonia gas produced in chamber 15 bubbles upwardly through the stand pipe. The diameter of this pipe is sufficient so that the gas bubbles through the liquid therein and does not lift slugs of liquid, as is the case in the smaller conduit 17.

The ammonia vapor from both the chambers 14 and 15 leaves the upper end of pipe 18 and passes through the conduit 20. Also, a certain amount of water vapor is inadvertently produced and flows along with the ammonia. In the rectifier 21 the temperature of the ammonia and water vapor is reduced to a point sufficiently low to condense substantially all of the water vapor, but not low enough to condense the ammonia. The water drains back to the upper end of stand pipe 18, while the ammonia vapor continues through the conduit 20 to the condenser 22.

In the condenser the temperature of the ammonia gas is reduced sufficiently to cause condensation at the pressure existing within the system. A certain amount of the ammonia is condensed in the upper part 23 of the condenser and drains into a vessel 25. However, the uncondensed portion of the ammonia passes through the vessel 25 in vapor form and continues through the lower part 24 of the condenser, where it is completely condensed and drains into vessel 26. The liquid ammonia from vessels 25 and 26 passes through conduits 31 and 32, respectively, to the parts 29 and 30 of the evaporator 27.

As will presently be explained, hydrogen gas flows upwardly through conduit 41 to the upper end of low temperature part 29 of the evaporator. The presence of the hydrogen in the evaporator part 29 causes the partial pressure of the ammonia introduced through the conduit 31 to be reduced, in accordance with Dalton's law, with a result that the ammonia evaporates, thus absorbing heat from the surroundings. The gaseous mixture of ammonia and hydrogen flows from the bottom of evaporator part 29 through conduit 33 to the upper end of evaporator part 30. At this point additional refrigerant is introduced through conduit 32 and it evaporates in the presence of the hydrogen. However, the hydrogen which is introduced into the evaporator part 30 already is admixed with the ammonia which evaporated in the part 29 and consequently the partial pressure of the ammonia in the part 30 is not as low as in the part 29. Consequently, the temperature at which the refrigerant evaporates is higher in the part 30 than in the part 29.

The gaseous mixture of ammonia and hydrogen leaves the evaporator part 30 through the

conduit 35. The conduit 34 is provided for the purpose of draining liquid from the lower end of evaporator part 29. Such liquid might be unevaporated ammonia or it might be water which was not completely separated from the refrigerant by the rectifier 21. The mixture of ammonia and hydrogen flowing through conduit 35 has a low temperature and, in flowing through inner pipe 37 of the heat exchanger 36 its temperature is raised by the warmer gas in jacket 38. Within the absorber 39 the mixture of ammonia and hydrogen is brought into intimate contact with the weak absorption solution with the result that the ammonia is absorbed and the hydrogen passes through the absorber and through conduit 40 to the jacket 38.

The absorption process results in the production of heat which is transferred to the fluid contained in the coil 50 in heat exchange relation with the absorber. The fluid in the coil 50 is thus caused to boil and the vapor passes through conduit 51 to the condenser 52 where its temperature is reduced sufficiently to liquefy it. The condensate flows through the conduit 53 to the lower end of coil 50.

The warm hydrogen flowing through jacket 38 serves to increase the temperature of the cold hydrogen-ammonia mixture within inner pipe 37, while at the same time the temperature of the hydrogen in jacket 38 is reduced. The hydrogen flows from the upper end of the jacket through conduit 41 to the low temperature part 29 of the evaporator.

The circulation of gases between and through the evaporator 27 and the absorber 29 results from the fact that the specific gravity of the mixture of ammonia and hydrogen flowing downwardly from the evaporator is greater than the specific gravity of the substantially pure hydrogen flowing upwardly from the absorber.

In Fig. 1, as just described, the evaporator parts 29 and 30 have been shown as being located side by side. This has been done in order that the various connections may be clearly shown and described. However, as pointed out in the introduction, it is desirable to have the lower temperature part 29 disposed within the higher temperature part 30. An evaporator constructed in this manner is illustrated in Figs. 2 through 5. As shown in these figures, the evaporator 27 includes an inner casting 60 and an outer casting 61 which are secured in spaced relationship by means of bolts 62 extending through spacing sleeves 63. Inner casting 60 is provided with a series of ice tray compartments 64 which are separated by means of shelves 65. The walls of casting 60 are formed with passages 66 through which extend conduits 67 which constitute the lower temperature part 29 of the evaporator. The upper end of conduit 66 is joined to conduit 41, which supplies the hydrogen gas from the gas heat exchanger. The lower end of conduit 67 is connected by means of the conduit 33 to the upper end of a conduit 68 which is received within passages 69 formed in the outer casting 61. Conduits 67 and 68 extend in serpentine form through the passages 69 formed in the casting and the lower end of conduit 68 is connected to the conduit 35 leading to the inner pipe 37 of the gas heat exchanger. Liquid ammonia is supplied to the upper end of conduit 67 through the conduit 31, while liquid ammonia is supplied to the upper end of conduit 68 through the conduit 32, as is clearly shown in Fig. 3. A plate 70 is secured to the front ends of cast-

ing 60 and 61 and is provided with an opening 71 in alignment with inner casting 60. A door 72 is hinged to plate 70 and serves to give access to the ice tray compartment 64. A series of heat transfer fins 73 are formed on the exterior of casting 61 in order to increase the surface available for the transfer of heat between the air within the cabinet 28 and the casting.

The circulation of fluids through the coils 67 and 68 of the evaporator shown in Figs. 2 through 5 is the same as that described in connection with Fig. 1 and hence need not be repeated. Due to the fact that the low temperature coil 67 is surrounded by the higher temperature coil 68, it is protected from the transfer of heat thereto from the comparatively warm air within the cabinet 28. Furthermore, a very low temperature may be maintained within the ice compartment without causing the temperature in the cabinet to fall to an undesirably low value.

It will be understood that the apparatus herein disclosed is given by way of example only and that modifications thereof fall within the scope of my invention, which is to be determined by the appended claims.

What is claimed is:

1. In an absorption refrigerating apparatus, a condenser, an absorber, a high temperature evaporator, a low temperature evaporator within said high temperature evaporator, means for supplying refrigerant from said condenser to both of said evaporators, means for supplying an inert gas from said absorber to said low temperature evaporator, and means for conveying a mixture of inert gas and gaseous refrigerant from said low temperature evaporator to said high temperature evaporator.

2. In an absorption refrigerating apparatus, a condenser, an absorber, a high temperature evaporator, a low temperature evaporator within said high temperature evaporator, means for supporting an ice tray within said low temperature evaporator, means for supplying refrigerant from said condenser to both of said evaporators, means for supplying an inert gas from said absorber to said low temperature evaporator, and means for conveying a mixture of gaseous refrigerant and inert gas from said low temperature evaporator to said high temperature evaporator.

3. In an absorption refrigeration apparatus, an insulated cabinet providing a food storage space, a condenser and an absorber outside of said space, a high temperature evaporator within said space, a low temperature evaporator within said high temperature evaporator, means for supporting an ice tray within said low temperature evaporator, means for supplying refrigerant from said condenser to both of said evaporators, means for supplying an inert gas from said absorber to said high temperature evaporator, and means for conveying a mixture of gaseous refrigerant from said low temperature evaporator to said high temperature evaporator.

4. In an absorption refrigerating apparatus, a generator, a condenser, a high temperature

5 evaporator, a low temperature evaporator within said high temperature evaporator, an absorber, means for conveying vaporous refrigerant from said generator to the upper end of said condenser, means for conveying liquid refrigerant from the lower end of said condenser to said high temperature evaporator, means for withdrawing liquid refrigerant from an intermediate point in said condenser and conveying it to said low temperature evaporator, means for conveying inert gas from said absorber to said low temperature evaporator, and means for conveying a mixture of gaseous refrigerant and inert gas from said low temperature evaporator to said high temperature evaporator.

10 5. In an absorption refrigerating apparatus, a condenser, an absorber, a high temperature evaporator, a low temperature evaporator within said high temperature evaporator, means for supplying refrigerant from said condenser to the upper ends of both of said evaporators, means for supplying inert gas from said absorber to the upper end of said low temperature evaporator, means for conveying a mixture of gaseous refrigerant and inert gas from the lower end of said low temperature evaporator to the upper end of said high temperature evaporator, and means for conveying a gaseous mixture from the lower end of said high temperature evaporator to said absorber.

20 6. In an absorption refrigerating apparatus, a condenser, an absorber, a high temperature evaporator, a low temperature evaporator within said high temperature evaporator, means for supplying refrigerant from said condenser to the upper ends of both of said evaporators, means for supplying inert gas from said absorber to the upper end of said low temperature evaporator, means for conveying a mixture of gaseous refrigerant and inert gas from the lower end of said low temperature evaporator to the upper end of said high temperature evaporator, conduit means connecting the lower end of said high temperature evaporator with said absorber, and means for draining liquid from the lower end of said low temperature evaporator to said absorber.

30 7. In an absorption refrigerating apparatus, a condenser, an absorber, a high temperature evaporator, a low temperature evaporator within said high temperature evaporator, means for supplying refrigerant from said condenser to the upper ends of both of said evaporators, means for supplying inert gas from said absorber to the upper end of said low temperature evaporator, means for conveying a mixture of gaseous refrigerant and inert gas from the lower end of said low temperature evaporator to the upper end of said high temperature evaporator, conduit means connecting the lower end of said high temperature evaporator with said absorber, and means forming a liquid sealed gas trap for conveying liquid from the lower end of said low temperature evaporator to said absorber while preventing passage of gas.

WILLIAM R. HAINSWORTH.
